UNITED STATES PATENT OFFICE.

ALBERT M. WOLTZ, OF BALTIMORE, MARYLAND, ASSIGNOR, BY MESNE ASSIGNMENTS, TO GRAND RAPIDS STORE EQUIPMENT CORPORATION, OF GRAND RAPIDS, MICHIGAN.

DIVISION-BOARD SUPPORT.

Application filed September 5, 1924. Serial No. 736,193.

This invention is a device for supporting the end of a division board, of the type employed to divide a drawer or the like into compartments.

5 One of the objects of the invention is to avoid the weakening practice of grooving the walls of a drawer or the like to receive the ends of division boards, by providing a simple device which may be detachably secured to a wall in any desired position, said device being constructed to have slidable engagement with a division wall. A further object is to provide a device with which the division board may be readily engaged or 10 disengaged, as occasion may require. A further object is to provide a supporting device so constructed that when the division board is in place, said device is completely concealed from view, and there are no exposed parts which might catch or injure fine fabrics, while they are being placed into or 15 removed from the compartments of the drawer.

The invention will be fully set forth and 20 particularly pointed out in the claims.

In the accompanying drawings:—

Figure 1 is a perspective view illustrating a drawer having the invention applied thereto.

30 Figure 2 is an enlarged detail sectional view of a portion of a drawer, illustrating the use of the invention. Figure 3 is a perspective view of the supporting device. Figure 4 is a sectional view on the line 4—4, 35 Figure 3. Figure 5 is a perspective view of a slight modification.

Referring to the drawing, 10 designates a drawer or other receptacle provided with side and end walls 11 and 10^a, respectively, 40 and divided into compartments 12, by means of division boards 13.

The division boards are held in place by suitable supporting devices the form of which as illustrated in Figures 2, 3, and 4, 45 consists of a strip of metal, the middle portion of which is bent back upon itself to form a middle guide portion 15. Contiguous to the ends of the body of the device, the material is flattened as indicated at 16, to 50 provide bearing portions lying in approximately the same plane as the rear edge of the device, but at right angles to the plane

of the guide portion. The extremities of the bearing portions 16 are bent over at right angles, and shaped to provide prongs 55 17, capable of being driven into the wood constituting the side or end walls of the drawer, or into the surface of a partition, as the case may be. The bearing portions 16 provide sufficient surface to prevent turning 60 of the support when in use.

It will be noted that the bearing portions 16 lie in a plane at right angles to the guide portion 15, and that the prongs 17 lie in planes at right angles to the bearing portions, and also at right angles to the guide portion. The division boards are provided with grooves 19 in their end edges, to receive the guide portion 15.

In practice, the prongs 17 are so disposed 70 that their planes will normally lie parallel with the grain of the wood of the wall into which they are to be driven. The devices may be readily secured in any desired position by driving the prongs 17 into the selected supporting surface. It is to be understood, of course, that two of the supporting devices will be provided for each division board 13, and are secured at opposite points 75 so that the grooved ends of the division 80 board may be engaged therewith or disengaged therefrom by a sliding movement.

In the modification illustrated in Figure 5 the body of the support is made of flat sheet metal 20, having punched out guide 85 portions 21, and provided with attaching prongs 22. This device is used in identically the same manner as that illustrated in the form previously described except that the punched out portions serve as the guide 90 means to engage the groove portion 18 of the division board, and the rear face of the strip between the protuberances 21, constitute bearing portions.

The advantages of the invention will be 95 readily understood by those skilled in the art to which it belongs. For instance, it is obvious that the supporting devices may be driven into the wood at any desired point, and the division board readily engaged 100 therewith or disengaged therefrom as occasion may require. If it should be desired to change the position of the division board all that is necessary is to pry the prongs

out of engagement and to drive them in at the new or selected position. An important advantage is that when the device is in use it is completely concealed by the division board, so that there are no projecting portions whatever, which may catch into fine fabrics which may be stored into the compartments.

Another advantage is that the prongs are so positioned that they will lie with the grain of the wood into which they are driven, and tendency to split the wood is thereby materially reduced.

Having thus explained the nature of the invention and described an operative manner of constructing and using the same, although without attempting to set forth all of the forms in which it may be made, or all of the forms of its use, what is claimed is:—

1. A division board support comprising a body provided with a relatively narrow guide portion and with bearing portions, said bearing portions extending laterally on both sides of said guide portion, and said body also having rearwardly projected approximately parallel prongs positioned to penetrate a supporting surface.

2. A division board comprising a metal

strip provided with a portion intermediate between its ends bent back upon itself to form a guide, said strip also having rearwardly projected approximately parallel attaching prongs at its ends, and widened bearing portions contiguous to the ends of said bent back portions.

3. A division board support comprising a strip of metal provided with a portion intermediate between its ends bent back upon itself to form a guide, the ends of said strip being widened with respect to the guide to provide relatively wide flat bearing portions, the end extremities of the strip being provided with rearwardly projected approximately parallel penetrating prongs.

4. A division board support comprising a body provided with a guide portion intermediate between its ends and laterally disposed bearing portions at the ends in a plane at right angles to the guide portion, said bearing portions having prongs arranged in planes at right angles to the plane of the main parts of the bearing portions, and also at right angles to the plane of the guide portion.

In testimony whereof I have hereunto set my hand.

ALBERT M. WOLTZ
